J. W. JONES

AUTOMATIC CAR COUPLER

Filed Oct. 15, 1923

Inventor
J.W.Jones,

By
Geo. P. Kimmel Attorney

UNITED STATES PATENT OFFICE.

JOHN WILL JONES, OF CLIFFORD, ILLINOIS.

AUTOMATIC CAR COUPLER.

Application filed October 15, 1923. Serial No. 668,723.

To all whom it may concern:

Be it known that I, JOHN WILL JONES, a citizen of the United States, residing at Clifford, in the county of Williamson and 5 State of Illinois, have invented certain new and useful Improvements in Automatic Car Couplers, of which the following is a specification.

This invention pertains to car couplings, 10 and has for its primary object, the provision, in a manner as hereinafter set forth, of a car coupling operating through the jar caused by the impact of the two cars to be coupled together, to give a quick and sure 15 coupling between the cars.

A further object of the invention is the provision of a coupling, in a manner as hereinafter set forth, which may be set by an attendant before the cars come together, 20 so that the said attendant may have sufficient time to get from between the cars, thus doing away with all possibility of injury to the attendant, the coupler acting through gravity, at the proper moment, to couple 25 the two cars together.

It is well known, that many fatalities occur amongst men engaged in coupling and uncoupling cars, particularly in coupling mining cars, where the men employed to 30 couple the cars together are obliged to ride upon the front of one of the cars and stay there until within a fraction of a second before the cars to be coupled come together. Should the coupler fail to get out from between the cars at the proper moment, he 35 would be caught and possibly fatally injured. In the use of the link and pin coupling, commonly employed at the present time, the coupler's life is constantly in danger, whereas in the use of my improved 40 coupling device, the engagement of one car with the other is automatic requiring no attention on the part of the coupler other than that of setting the link in the proper 45 position before the cars are brought together.

A still further object of this invention is the provision, in a manner as hereinafter set forth, of a means for quickly uncoupling 50 the car, which means is operable from the outer side of the car, and is easily operated and positive in its action.

A still further object is the provision, in a manner as hereinafter set forth, of a coupler which will be quick and positive in its 55 action, strong, durable, easily manipulated

and therefore requiring little attention, and inexpensive to manufacture.

The invention will be best understood from a consideration of the following detailed description taken in connection with the accompanying drawings forming part of this specification, with the understanding that the invention is not confined to any strict conformity with the showing of the drawings, but may be changed and modified so long as such changes and modifications mark no material departure from the salient features of the invention as expressed in the appended claims.

In the drawings:—

Figure 1 shows a structure embodying this invention, set in position and ready for coupling.

Fig. 2 shows the action of the coupling member at the moment of impact between the two cars.

Fig. 3 shows the position of the parts after the connection of the coupling members when the cars have pulled apart.

Fig. 4 is a detail perspective of the coupling embodying this invention, and

Fig. 5 is a detail perspective of a modification of the device.

In the drawings, wherein like reference numerals indicate corresponding parts throughout the several views of the drawings, there is shown in dotted position end portions of two cars 1 and 2, of the type commonly used in coal mines, and for which this device is primarily intended although of course it may be used upon other types of cars. The sills of the cars at their ends, are indicated as having near their central parts, spaced bumpers 3.

The coupling mechanism embodying this invention comprises a draw bar 4 adapted to be secured to one of the cars between the bumpers 3, and a link supporting bar 5, to be positioned upon the sill of the opposite car between the opposite bumpers. As clearly shown in Fig. 4, the draw bar 4 is flat where it contacts with the surface of the sill, and has its forward end constricted and formed to provide a bearing 6 and a hook 7 which extends beyond the edge of the sill between the bumpers 3.

Pivoted at 8 upon one side face of the bill portion of the hook 7, is a curved arm 9 adapted to pass over the interior of the hook 110 when moved on its pivot. A bearing 6 is formed on the draw bar, and rotative

through this bearing is a rod 12 having lateral handles 13 at the ends, the latter located beyond the sides of the car frame, so that the rod can be actuated from outside the lines of the cars. Formed in the rod 12 substantially in line with the arm 9 is a lateral bend 11, and coupled to this bend and to the free end of the arm 9 is a link 10. By this means it will be obvious that when the rod 12 is rotated in the bearing 6 by force applied to either of the handles 13, the arm 9 will be caused to swing on its pivot 8.

A flat link supporting member is carried upon the opposite car and comprises a flat bar 5 having its forward end bifurcated as shown at 13 and extending beyond the edge of the sill above and between the bumpers 3. Each of the furcations has its upper side cut down half way between its ends as indicated at 14. This cut down portion extends about half way through the thickness of the furcation and is then continued forward to its free end at a slight upward inclination, the thickness of the end of each furcation being slightly greater than its central portion and less than the thickness of the original member. As also shown, each of the cut out portions is bevelled toward the inner side of the furcations thus forming a seat for the connecting link to be described further on. Secured to the sill of the car beneath the bifurcated end of the bar 5, is a U-link 16, having its looped ends 17 secured by a bolt or other appropriate means to the sill of the car. This looped link carries an intermediate link 18 which in turn carries an oval connecting link 19 which link is divided and reinforced near its larger end by a cross member 20 which member serves to prevent the link 19 from turning around the link 18.

In the modification shown in Fig. 5, the link 18 instead of being carried by a U-link connected to the sill of the car, is carried upon a cross pin 21 which extends through the furcations 13 approximately midway their ends. This type of connection is intended to be used in small mines where the bumpers on the cars are very short, thus the link 19 will not be thrown so far forward when the bumpers of the two cars are brought together.

The operation of this device is as follows: 55 When the cars are to be coupled together

the large end of the enlarged link 19 is seated in the cut out portions 14 of the bifurcated plate 5, and tilted back until the upper end of the link rests against the body of the car. The cars are then brought forcibly together, and the force of the impact tends to throw the upper end of the link 19 forward, so that it will drop over the bill of the hook 7 of the draw bar carried on the opposite car. When the cars are drawn apart, the end of the link slides down the inclined surface of the hook and sets up a positive engagement therewith.

When it is desired to uncouple the cars, the attendant takes up a position upon the outside of the car 1, lifts the handle 13, thus causing the bar 12 to revolve and lift the loop 11, drawing upward with it the link 10 and the free end of the arcuate shaped member 9.

As may be seen when the arcuate shaped member 9 is swung upward, it will carry with it the end of the link 19 until it reaches the point where the inner edge of the member 9 becomes flush with the upper edge of the hook 7 whereupon the link 19 will slip over the end of the hook 7 thus allowing the coupling members to fall apart and release the cars.

What I claim is:—

1. In a car coupling, a supporting member having an upwardly opening seat, and adapted to be attached to a car body, a main link initially resting at the lower end in said seat and adapted to bear at the other end against the car body, a coupling link engaging said main link and adapted to be connected to said car body, said main link adapted to be displaced by the concussion with another car and engage over a hook on said other car.

2. In a car coupling, a supporting member adapted to be attached to a car body and having an open recess in one end and upwardly opening seats at the sides of the recess, a main link initially resting at the lower end in said seats and adapted to be movably supported against the car body, and a holding link extending through said recess and engaging said main link and adapted to be held from movement relative to said car body.

In testimony whereof, I affix my signature hereto.

JOHN WILL JONES.
